UNITED STATES PATENT OFFICE

141,222

DESIGN FOR A CHAIR FRAME

Ralph Rapson, Chicago, Ill.

Application March 24, 1945, Serial No. 118,671

Term of patent 3½ years

(Cl. D15—1)

To all whom it may concern:

Be it known that I, Ralph Rapson, a citizen of the United States of America, residing at Chicago, in the county of Cook and State of Illinois, have invented a new, original, and ornamental Design for a Chair Frame, of which the following is a specification, reference being made to the accompanying drawing, forming a part thereof.

The single figure in the drawing is a side perspective view of a chair frame showing my new design.

I claim:

The ornamental design for a chair frame, substantially as shown.

RALPH RAPSON.
